DESIGN FOR A BELT SANDER

Herbert E. Tautz, Milwaukee, Wis., assignor to
The Delta Manufacturing Company, Milwaukee,
Wis., a corporation of Wisconsin

Application November 11, 1937, Serial No. 72,807

Term of patent 7 years

To all whom it may concern:

Be it known that I, Herbert E. Tautz, a citizen of the United States, residing at Milwaukee, in the county of Milwaukee and State of Wisconsin, have invented a new, original, and ornamental Design for Belt Sanders, of which the following is a specification, reference being had to the accompanying drawing, forming part thereof.

In the drawing,

Fig. 1 is a side elevation of a belt sander showing my new design;

Fig. 2 is an elevation of the other side thereof;
Fig. 3 is a top plan view;
Fig. 4 is a front elevation, and
Fig. 5 is a rear elevation.

I claim:
The ornamental design for a belt sander, as shown.

HERBERT E. TAUTZ.
